CLAIM

We claim the ornamental design for a cosmetic cap, as shown and described.

DESCRIPTION

FIG. 1 is a top perspective view of a cosmetic cap showing our new design;

FIG. 2 is a front view of the cap shown in FIG. 1;

FIG. 3 is a back view of the cap shown in FIG. 1;

FIG. 4 is a right side view of the cap shown in FIG. 1;

FIG. 5 is a left side view of the cap shown in FIG. 1; and

FIG. 6 is a top view of the cap shown in FIG. 1.

The evenly-dashed broken lines in the drawings illustrate the portions of the cosmetic bottle that form no part of the claimed design.
